UNITED STATES PATENT OFFICE.

BARTLETT KRUSBERGER, OF MERIDEN, CONNECTICUT.

PERMUTATION SWITCH LOCK.

1,414,192.

Specification of Letters Patent. Patented Apr. 25, 1922.

Application filed July 11, 1921. Serial No. 483,879.

To all whom it may concern:

Be it known that I, BARTLETT KRUSBERGER, a citizen of the United States, residing at Meriden, in the county of New Haven and State of Connecticut, have invented certain new and useful Improvements in Permutation Switch Locks; and I do declare the following to be a full, clear, and exact description of the invention, such as will enable others skilled in the art to which it appertains, to make and use the same.

This invention relates to an improved lock for use in connection with the switch of an automobile and one object of the invention is to provide a lock having a housing to be secured at opposite relation to the switch upon the instrument board and having a key extending through the housing and carrying a switch engaging element, permutation means being provided to control sliding and rotary movement of the plunger key.

Another object of the invention is to so construct the permutation tumblers and key that when the key is in an inoperative position with respect to the switch, the permutation tumblers may have rotary movement independent of the key and to further so construct the key and tumblers that when the key is moved longitudinally into an operative position with respect to the switch, the tumblers may be turned with the key.

Another object of the invention is to provide improved means for rotatably mounting the tumblers and slidably and rotatably mounting the key, this mounting means serving not only to rotatably mount the tumblers but further serving to prevent rotary movement of the key when in an inoperative position with respect to the switch and further serving to limit rotary movement of the key when in an operative position and prevent longitudinal movement of the key to an inoperative position after the plunger key has been turned to move the switch.

Another object of the invention is to provide a lock which will be very compact and will be well protected.

Another object of the invention is to provide a lock in which the parts forming the same can be easily taken apart for repairing or changing the combination and then easily put together again.

This invention is illustrated in the accompanying drawings, wherein:

Figure 1 is a view in elevation looking at the outer end of the lock.

Figure 2 is a vertical longitudinal sectional view through the lock.

Figure 3 is a view showing the outer tumbler in end elevation. 60

Figure 4 is a view showing the tumbler of Fig. 3 in side elevation.

Figure 5 is a view showing the inner tumbler in end elevation.

Figure 6 is a view showing the tumbler of Fig. 5 in side elevation. 65

Figure 7 is a view showing the intermediate tumbler in end elevation.

Figure 8 is a view showing the tumbler of Fig. 7 in side elevation. 70

Figure 9 is a view showing the bearing sleeve in end elevation.

Figure 10 is a view showing the bearing sleeve in side elevation.

Figure 11 is a view showing the switch engaging element in end elevation. 75

Figure 12 is a view showing the switch engaging element in side elevation.

Figure 13 is a view showing the tumbler casing in side elevation. 80

Figure 14 is a side elevation of the tumbler casing taken at right angles to the showing in Fig. 13.

Figure 15 is a transverse sectional view through the plunger key. 85

This switch lock is provided with a housing 1 which is provided with a head at its outer end and adjacent its open end is provided with internally threaded sockets 2 for receiving securing bolts which will be passed through the instrument board. The lock will thus be securely but releasably held in engagement with the instrument board with the housing positioned about the ordinary switch. The switch will thus be enclosed in the housing and cannot be adjusted unless the combination of the lock is known. 90

A block 3 is secured in the upper portion of the housing 1 and carries a U-shaped tumbler casing 4, one depending arm of which engages the inner face of the head of the housing 1 and the second arm of which is positioned intermediate the closed and open ends of the housing. These arms 5 and 6 are provided with openings 7 and 8, the opening 7 being relatively large and registering with an opening formed in the head of the housing 1, and the opening 8 being smaller. A tongue 9 extends into the opening 8 as shown in Fig. 14 for a purpose 100 to be hereinafter brought out. 105

The tumblers 10, 11 and 12 are positioned

in the tumbler casing 4 and each is provided with a hub extension 13 so that the tumblers will be spaced as shown in Fig. 2. In addition to the hub extensions 13, the tumbler 10 is provided at its opposite side with a second hub extension 14 for extending through the registering opening in the arm 5 of the casing and head of the housing 1. The tumblers are each provided with a passage 15 resembling a key-hole opening. These key-hole passages 15 of the tumbler disks will be enlarged to provide pockets 16 which are circular in shape and of a diameter corresponding to the greatest diameter of the key-hole passage. In order to rotatably mount these tumblers, there has been provided a bearing sleeve 17 which passes through the tumblers and having one end fitting into the opening 8 of the arm 6. A notch or recess 18 is provided to receive the tongue 9 and thus provide means to prevent the bearing sleeve from having rotary movement. This bearing sleeve is provided with a longitudinally extending slot 19 and is further cut to provide recesses 20 which extend from the sides of the slot 19. It will thus be seen that when assembling it is simply necessary to put the tumbler 10 in place and then put the tumblers 11 and 12 in place and pass the bearing sleeve through the passages 15 of the tumblers until the end of the bearing sleeve fits into the opening 8 and the tongue 9 fits into the notch 18. The tumblers will thus be rotatably mounted and may be turned to a desired position. In order to permit rotary movement to be transmitted from one tumbler to another, there has been provided pins 21 which will be brought into contact to impart rotary movement as will be hereinafter brought out. The tumblers will be provided with a plurality of pin receiving openings 22 so that by transferring the pins to different openings, the combination may be changed.

After the tumblers have been put in place, the setting block 23 will be put in place. This setting block is provided with a passage 24 for registering with the interior of the bearing sleeve 17 as shown in Fig. 2, the passage being enlarged to provide a pocket 25 for receiving the extended hub extension 14 of the tumbler 10. Securing screws 26 are passed through openings 25 formed in the setting block and screwed into threaded openings or sockets 27 formed in the hub extension 14. These screws securely but releasably connect the setting block with the tumbler 10 so that the tumbler 60 can be turned through the medium of the setting block. In order to assist in operatively connecting the setting block with the tumbler 10, there has been provided a pin 28 which fits into pockets formed in the 65 setting block and hub extension as shown

in Fig. 2. After the setting block has been connected with the hub extension of the tumbler 10, the plunger key 29 will be passed through the passage 24 and through the bearing sleeve. This plunger key is provided with lugs 30 which will pass through the slot 19 and may move up into the recesses 20 when the key is turned. A block 31 is secured upon the plunger key at the proper distance from the collar 32 so that the plunger key will be permitted of limited longitudinal movement. Lugs 33 extend from this block for engaging the switch and turning the same to an adjusted position when the key is in the position shown in Fig. 2.

When this lock is in use, it will be assembled as shown in Fig. 2 and will be connected with the instrument board in operative relation to the switch by suitable securing screws passing through the instrument board and screwed into the threaded sockets 2. Ordinarily, the key will be drawn outwardly so that the block 31 moves out of engagement with the switch and will be positioned close to and preferably in contact with the arms 6 of the tumbler casing 4. The lugs 30 of the key will then be positioned in the pockets 16 of the tumblers and the tumblers can be rotated to scatter or set the combination. With the combination scattered, the key cannot be moved inwardly to engage the switch and it will thus be seen that the switch cannot be turned unless the proper combination is known.

When setting the combination, the setting block will first be turned toward the right in Fig. 1 a number of times and as it turns the pin 21 of the tumbler 10 will first engage the co-operating pin of the tumbler 11 thus turning the tumbler 11 with it and eventually bringing the second pin 21 of this tumbler 11 into engagement with the pin of the tumbler 12. The three tumblers will thus all be turned together toward the right and rotation will be continued until the tumbler 12 has been turned to a position to position the reduced portion of its key-hole passage 15 in registry with the slot 19 of the bearing sleeve 17. Of course, the numbers marked about the edge portion of the setting block will have to be watched so that turning the block to the right can be stopped when the proper number has been brought into a position above the marker 35 carried by the 115 housing 1. After the tumbler 12 has been properly set, the block will then be turned to the left and will be turned until the pin 16 of the tumbler 10 has made a complete revolution and brought into engagement with the 120 pin of the tumbler 11. Continued rotation of the block toward the left will then move the tumbler 11 toward the left until the reduced portion of this tumbler is moved into 125 position to register with the slot 19 of the 130

bearing sleeve. The bearing block will then be turned toward the right until the reduced portion of its key-hole passage is in position to register with the slot of the bearing sleeve. 5 A spring strip 36 is provided to engage the peripheries of the tumblers 11 and 12 and thus permit of their being frictionally held in the set position. With the tumblers all in the proper position, the key can then be 10 moved longitudinally to the position shown in Fig. 2, with the lugs 30 moved out of the pockets and into the reduced portions of the key-hole passages 15. The lugs 33 will now be in engagement with the switch and when 15 the key is turned, the switch will be moved to the adjusted position. When the key is turned, the lugs 30 move up into the notches or recesses 20 of the bearing sleeve and thus 20 rotary movement of the key beyond a desired amount is prevented. With the switch turned on and the lugs 30 of the key positioned in the recesses 20, the key cannot be moved out of engagement with the switch. It should be further noted that when the key 25 is turned, the tumblers will also be turned due to the fact that the lugs 30 of the key are positioned in the reduced portions of the key-hole passages of the tumblers. Therefore, the combination cannot become scattered and further there is no danger of the 30 key slipping out of engagement with the switch. When it is desired to turn the switch off, the key is simply turned back to the original position. The key can then 35 be drawn outwardly until the block 31 is brought into engagement with the arm 6 of the tumbler casing and the lugs 30 of the key will then again be positioned in the pockets 16 of the tumblers. By holding the 40 key and turning the setting block, the combination can be scattered and the switch cannot then be again turned on unless the combination is known. When it is desired to change the combination, it is simply necessary 45 to take the lock apart and move one or more of the pins 21.

I claim:

1. A lock comprising a housing, tumblers in said housing receiving rotary movement one from another, setting means carried by one of said tumblers, a sleeve rotatably mounting said tumblers and slotted longitudinally, a key slidably and rotatably passing through the setting means and 50 sleeve, and lugs carried by said key and passing through the slot for engaging said tumblers, the tumblers through engagement by said lugs releasably holding the key against movement longitudinally to an operative position and the lugs engaging the tumblers to rotate the tumblers with the key when the key is moved to an operative position. 55

2. A lock comprising a housing, tumblers in said housing and receiving rotary move-

ment one from another, a setting block connected with one of said tumblers, the setting block and tumblers being provided with registering openings forming a key-hole passage extending through the block and tumblers and within the tumblers being enlarged to form annular pockets, a bearing sleeve extending through the registering openings of the tumblers to rotatably mount the tumblers, the sleeve being longitudinally slotted and having recesses leading from the slot between the annular pockets of the tumblers, and a key passing through the block and sleeve and provided with lugs extending through the slot of the sleeve into the reduced portion of the key hole passage. 65 70 75 80

3. A lock comprising a housing, a support in said housing, a bearing sleeve carried by said support and having a longitudinally extending slot and recesses leading from the sides of the slot, tumbler disks loose upon said sleeve and provided with pockets and key hole passages receiving said sleeve, means for transmitting rotary movement from one tumbler to another, a setting block connected with one of said tumblers and provided with a key hole passage for registering with the key hole passage of the tumbler, a key slidably passing through the setting block and sleeve and provided with side lugs extending through the slot of 85 90 95 said sleeve for fitting into the pockets and reduced portions of the key hole passages of the tumblers, longitudinal adjustment of said key moving the lugs from a position in the pockets permitting 100 rotation of the tumblers independent of the key to a position in the key hole passages holding the tumblers in a set position upon the key, rotary movement of the key and tumblers being limited through passage of 105 said lugs into said recesses.

4. A lock comprising a housing having a head provided with an opening, a casing in said housing, openings aligned with the opening in the head of said housing, a bearing sleeve extending through the openings in the housing and casing, and held against rotation, tumbler disks rotatably carried by said sleeve, one of said disks having a hub extension extending through the opening in 110 the head of said housing, a setting block releasably connected with the extended hub of said disk, means for transmitting rotary movement from one disk to another, a key extending through the setting block, bearing 115 sleeve and housing, switch engaging means carried by said key, and means carried by said key for holding the key against rotary movement when the key is in an inoperative position and for holding the tumblers 120 against rotary movement independent of the key when the key is moved longitudinally into an operative position, said tumblers 125

having rotary movement independent of the key when the key is in an inoperative position.

5. A lock comprising a housing having 5 a head provided with an enlarged opening, a casing in said housing having spaced arms provided with openings alined with the opening in the head of said housing, a setting block having a key hole opening communicating with a pocket registering with the opening in the head of said housing, tumbler disks in said casing each provided with a hub provided with a pocket and a key hole passage communicating with the 10 pocket, the hub of one tumbler extending through the casing and head of the housing into the pocket in said setting block, a bearing sleeve extending through the hubs of 15

said tumblers and held against rotary movement and provided with a longitudinally extending slot and side notches leading from the slot, means connecting the setting block with the extended tumbler hub, means for transmitting rotary movement from one tumbler to another, a plunger key extending 20 through the setting block and bearing sleeve and through said housing, lugs carried by said plunger key for passing through the slot of the sleeve when the plunger key is moved longitudinally and moving into the 25 side notches thereof when the plunger key is rotated, and switch engaging means carried by said plunger key.

In testimony whereof I have hereunto set my hand.

BARTLETT KRUSBERGER.
